GAME BOARD OR THE LIKE

Aaron G. Cohen, Los Angeles, Calif., and Michael C. Mills, Middlesex, and Dermot Sims, Piscataway, N.J., assignors to Mattel, Inc., Hawthorne, Calif.

Filed Aug. 5, 1970, Ser. No. 24,586

Term of patent 14 years

Int. Cl. D21—01

U.S. Cl. D34—5

FIG. 1

FIG. 2

FIG. 3

FIG. 4

FIG. 5

FIG. 1 is a perspective view taken from the top of a game board embodying our design;

FIG. 2 is a top view of same;

FIG. 3 is a bottom view thereof;

FIG. 4 is a side view, the remaining three sides being substantially identical thereto; and

FIG. 5 is a sectional view taken substantially at 5—5 of FIG. 2.

We claim:

The ornamental design for a game board or the like, as shown and described.
